Primary Examiner — Susan Bennett Hattan*Assistant Examiner* — Marie Fast Horse(74) *Attorney, Agent, or Firm* — Baker & McKenzie LLP(57) **CLAIM**

The ornamental design for a ceiling fan housing with light fixture, as shown and described.

DESCRIPTION

FIG. 1 is a perspective view of a ceiling fan housing with light fixture in accordance with my design;

FIG. 2 is an enlarged perspective view of the ceiling fan housing with light fixture in accordance with my design; FIG. 3 is an enlarged top plan view of the ceiling fan housing with light fixture in accordance with my design, the opposite side being identical thereto;

FIG. 4 is an enlarged bottom plan view of the ceiling fan housing with light fixture in accordance with my design; FIG. 5 is an enlarged front side view of the ceiling fan housing with light fixture in accordance with my design, the rear side being identical thereto; and, FIG. 6 is a enlarged left-side elevation view of the ceiling fan housing with light fixture in accordance with my design, the opposite side being identical thereto.

The broken-line disclosure of elements is understood to represent portions of the article in which the design is embodied, but which form no part of the claimed design.

1 Claim, 3 Drawing Sheets(56)
